[57] CLAIM

The ornamental design for a wrist watch, as shown and described.

DESCRIPTION

FIG. 1 is a front elevational view of a wrist watch showing my new design;

FIG. 2 is a right side elevational view;

FIG. 3 is a left side elevational view;

FIG. 4 is a rear elevational view;

FIG. 5 is a top plan view; and

FIG. 6 is a bottom plan view.

The broken line showing of a wrist band is for illustrative purposes only and form no part of the claimed design.

The characteristic feature of the design resides in the narrow flat rectangular bezel with chamfered corners.
